ATTORNEY.

UNITED STATES PATENT OFFICE.

SIEGFRIED J. VARNHAGEN, OF SAN FRANCISCO, CALIFORNIA.

DESIGN FOR A CHILD'S GARMENT OR ROMPER.

59,570.

Specification for Design.

Patented Nov. 1, 1921.

Application filed May 31, 1921. Serial No. 473,907. Term of patent 7 years.

To all whom it may concern:

Be it known that I, SIEGFRIED J. VARNHAGEN, a citizen of the United States, residing at San Francisco, in the county of San Francisco and State of California, have invented a new, original, and ornamental Design for a Child's Garment or Romper, of which the following is a specification, reference being had to the accompanying drawing, forming part thereof.

In the drawing:

Fig. 2 is a back view of the garment.

I claim:

The ornamental design for a child's garment or romper, as shown.

In testimony whereof, I have hereunto set my hand this 21st day of May, 1921, in the presence of the two subscribed witnesses.

SIEGFRIED J. VARNHAGEN.

Witnesses:

J. H. MORGAN,
J. C. VAUGHAN.
